CLAIM

The ornamental design for a tire, as shown and described.

DESCRIPTION

FIG. 1 is a perspective view of a tire showing our new design it being understood that the tread pattern is repeated throughout the circumference of the tire, the opposite side being substantially the same as that shown; FIG. 2 is a front elevational view thereof;

FIG. 3 is a side elevational view thereof;

FIG. 4 is an enlarged fragmentary plan view thereof; FIG. 5 is a perspective view of a tire showing a second embodiment of our new design;

FIG. 6 is a front elevational view of the tire of FIG. 5; FIG. 7 is a side elevational view of the tire of FIG. 5; and

FIG. 8 is an enlarged fragmentary plan view of the tire of FIG. 5.
